UNITED STATES PATENT OFFICE.

CHARLES F. SCHMELZ, OF BRIDGEPORT, CONNECTICUT, ASSIGNOR TO CURTIS & CURTIS CO., OF BRIDGEPORT, CONNECTICUT, A CORPORATION OF CONNECTICUT.

PIPE THREADING AND CUTTING-OFF MACHINE.

Application filed December 8, 1924. Serial No. 754,498.

To all whom it may concern:

Be it known that I, CHARLES F. SCHMELZ, a citizen of the United States, residing at the city of Bridgeport, in the county of Fairfield and State of Connecticut, have invented certain new and useful Improvements in Pipe Threading and Cutting-Off Machines; and I do declare the following to be a full, clear, and exact description of the invention, 10 such as will enable others skilled in the art to which it appertains to make and use the same.

This invention relates to pipe threading and cutting off machines, and more particularly to that class thereof in which the pipe or work is held stationary while the threading dies as well as the cut off tool are revolved around it.

My invention has for one of its objects 20 the provision of a machine of this character in which the main gear or die carrier may be moved forward or rearward in its supporting shell or housing by a hand lever which is permanently connected with said gear by intervening mechanism including a grooved 25 ring on the gear, this grooved ring performing the triple function of first, acting as a continuous bearing member for the gear in the shell, second, forming the element where- 30 by the gear may be moved longitudinally in the shell (through shoes and the lever above mentioned), and third, serving as one wall of a lubricant chamber from which oil may be automatically distributed to the interior 35 of the shell, to the several threading dies, and also to the cut off tool, during the opera- 40 tion of the machine.

A further object of the invention resides 45 in the provision of means whereby the main gear or die carrier may be locked against longitudinal sliding movement in the shell during the cutting off operation, these locking means being effective at any position of the gear in the shell.

Other objects of the invention will hereinafter appear and will be particularly defined in the claims.

In the accompanying drawings

Figure 1 is a front view of a machine embodying my invention—

Figure 2 is a side view of the same—

Figures 3 and 4 show detail broken views

of the trip-pin used for the cutting-off device—

Figure 5 is a sectional detail of one of the 55 shoes whereby the main gear is moved longitudinally in the shell—

Figure 6 represents a central horizontal section of the machine, and

Figure 7 is a front view of the main gear 60 and the dies carried thereby, the front ring and the face plate having been removed.

In the drawings, 10 denotes the main shell of the machine having at the rear end thereof ways 11 between which are guided for 65 vertical movement a pair of pipe jaws 12, 13, which may be opened and closed by screws 14 each of which is provided with right and left hand threads in engagement with said jaws, respectively, as usual. Each 70 screw 14 has at its upper end a gear 15 seated against a top plate 16 and engaged by another gear 17 whereby both gears 15 are rotated and therefore move both screws and consequently both jaws simultaneously. 75 By referring to Figure 1 it will be noted that the work (indicated by a pipe P) is grasped at substantially three points to maintain the same stationary.

Mounted for rotation as well as longitudinal reciprocation in the shell 10, is the main gear 20 (see Figure 6) which carries all of the active work-elements (such as the threading dies D and also the cut-off tool T), the rotation being clockwise for cutting right hand threads, and vice versa for cutting left hand threads. This main gear or die-carrier has peripheral teeth 21, and the outside diameter of the ring is slightly smaller than the inside diameter of the shell 90 so as to establish an annular space all around the gear which is provided, however, at its front end with a steel ring 22, and at its rear end with a similar ring 23, these two spaced rings constituting not only the bearing members for supporting the gear in the shell, but also serving as side walls of a lubricant chamber which receives a supply of oil through a pipe 24 leading into the interior of the shell (see Figures 1 and 2) and which extends all around the gear between the two rings, as will be readily understood. 95

The dies D, four in number, are seated in radial slots 25 in the main gear and may be 100

adjusted by a cam ring 26 suitably supported by the main gear, the cam faces 27 of which ring engage the outer ends of said dies, while correspondingly formed grooves 28 in the ring in engagement with the die-pins 29 are adapted to "open" all the dies simultaneously when the cam-ring is rotated anti-clockwise on the main gear. The die adjustment which is thus provided will enable threads of standard size, oversize or undersize, to be cut.

A face plate 30, secured to main gear by screws 31, serves to hold the dies as well as the cam in position on the main gear.

15 Rotation is imparted to the main gear 20 by a pinion 35, the shaft 36 of which is journaled in bushings 37 held on the shell by a cap 38 which entirely encloses the pinion and permits the oil from the shell to surround 20 said pinion which is of such length as to permit the main gear to move longitudinally in the shell without interference with the rings 22, 23, and yet allow a full length thread to be cut. The shaft 36 carries at its 25 rear end a gear 39 which may be driven from any convenient source.

Lubricant is supplied continuously to each of the dies, as follows:—

30 An oil channel 40 (for each die) extends radially from a tooth space of the main gear to a point where it intersects a longitudinal duct 41 which, in turn, has a pair of radial outlets 42 so situated that the oil will be delivered directly in front of the cutting face 35 of the dies (see Figures 6 and 7). The flow of oil may be regulated by a needle valve 43 the stem of which is in screw thread engagement with the face plate, while its rear or 40 needle end is adapted to control the opening of the duct 41 near its point of intersection with the channel 40.

A similar oiling organization is provided for the cut off tool T above mentioned and shown in Figure 6, in which 45 denotes a block secured to the face plate 30 and having a recess 46 in which a nut 47 travels as it is operated by a screw 48, the nut 47 having a pin connecting it with the cut off tool, while the screw 48 has at its outer end a star wheel 49 which is adapted to be intermittently rotated by a trip pin 50 to be hereinafter described. In this instance a radial channel 51 leads from a tooth space to the longitudinal duct 52 the front end of which connects with 55 a radial groove 53 in the front face of the face plate adjacent to the cutting tool, so that the oil will be conducted directly against the back face of the latter and toward the inner or cutting end thereof. A 60 needle valve 54 serves to control the flow of oil through the duct 52.

From the above it will be understood that each of the dies and also the cutting off tool are individually subject to lubrication as controlled by their several needle valves, re-

spectively, and irrespective of the position of the main gear in the shell.

As before stated, in the present type of machine, the pipe P is clamped in the jaws against rotary as well as longitudinal movements. Hence, when the pipe end is to be threaded, the main gear must be moved rearwardly in the shell until, at least, the dies have cut a few convolutions, after which this "feeding-in" movement becomes automatic, similar to that of a hand die stock. This primary longitudinal movement is imparted to the main gear by an arched lever 70 pivoted near its opposite ends on studs 56 and connected by links 57, 58, with a pair of pressure bars 59, 60, each of which is 75 slidable in a recess *a* in the shell and has a shoe 61 (see Figures 5 and 6) riding in the groove 62 of the front ring 22 above referred to, the shell rim being slotted, as at 63, to 80 permit the stem of the shoe to travel rearwardly. A packing 64 secured to each bar serves to prevent leakage of oil at this point. Now, inasmuch as the longitudinal positions 85 of the main gear and both pressure bars always remain the same relatively to each other, and as, furthermore, the cut-off block is carried by the main gear, I have provided in connection with the left bar 59, the trip 90 pin 50 above mentioned, so that for each rotation of the main gear the star wheel 49 will be turned one point and thus feed the cutting off tool inwardly in a step-by-step manner. While the machine is threading, the 95 cut off tool must naturally be out of commission, and for this reason the trip pin 50 may be withdrawn from its active position shown in Figures 1, 2, and 6. By referring to Figure 3 it will be seen that the pin 50 has a pair of recesses 65, 66, adapted to receive a spring pressed ball 67 which hold 100 the pin against accidental sliding movement when in either projected or retracted position, and which furthermore hold the pin against rotation, it being rather essential 105 that the nose of the trip pin, which is cut away as shown in Figure 4, shall retain that position to prevent "crowning" of the star wheel points on the pin nose. When the pin has been withdrawn sufficiently to have the 110 ball 67 seated in the recess 66, the nose is out of reach of the star wheel, and vice versa.

When it is desired to cut off the pipe, the main gear must be stationary, longitudinally, it being understood, of course, that the threading dies are then out of action and withdrawn by an anti-clockwise movement of the cam 26 above described. The main gear is locked against longitudinal movement by a "rider" 70 the rear end of which 120 is slotted and straddles a clamping screw stud 71 threaded in the shell, while its forward end is pivoted to one of the ends of the arched lever 55.

It will be understood that the main gear 125

may be moved by hand back and forth in the shell as long as the clamp screw 71 is loose, so that, rather than move the pipe longitudinally to meet the required position for cutting-off, the gear may be moved to bring the cutting-off tool into the desired position on the pipe clamped in the jaws of the machine, without interfering with the supply of the necessary lubrication from the interior of 10 the shell.

Having thus described my invention what is claimed is:—

1. A machine of the character described, comprising a shell, a die carrier gear circumferentially spaced from said shell and having rings at its ends whereby said gear is journaled in said shell, an enclosed pinion extending within said shell and in mesh with said gear, and means for supplying a lubricant within the space between said shell and gear.

2. In a machine of the character described, the combination of a shell, a die carrying gear rotatably journaled at its ends within 25 said shell and spaced from the latter intermediate said journals, an enclosed pinion in mesh with said gear, threading and cutting off dies carried by said gear, means for supplying lubricant within the space between said gear and shell, and ducts communicating with said space and leading to 30 said dies for supplying lubricant to the latter.

3. A machine of the character described, comprising a shell, a die carrier gear rotatable in said shell and having spaced bearing rings forming in conjunction with the interior wall of the shell an oil chamber, dies carried by said gear, ducts formed in said 40 gear for conducting oil from said oil cham-

ber to said dies respectively, and means for supplying oil to said chamber.

4. A machine of the character described, comprising a shell, a die carrier gear rotatable in said shell and having spaced bearing 45 rings forming in conjunction with the interior wall of the shell an oil chamber, dies carried by said gear, ducts formed in said gear for conducting oil from said oil chamber to said dies respectively, means for supplying oil to said chamber, and means for controlling the flow of oil through said ducts.

5. A machine of the character described, comprising a shell, a die carrier gear rotatable in said shell and having spaced bearing rings forming in conjunction with the interior wall of the shell an oil chamber, threading and cutting off dies carried by 55 said gear, means for manually shifting said gear longitudinally within said shell, means 60 for supplying oil to said chamber, and ducts leading from the latter to said dies for supplying oil to the dies.

6. A machine of the character described, comprising a shell, a die carrier gear rotatable in said shell and having spaced bearing rings forming in conjunction with the interior wall of the shell an oil chamber, threading and cutting off dies carried by 65 said gear, means for manually shifting said gear longitudinally within said shell, means 70 for supplying oil to said chamber, ducts leading from the latter to said dies for supplying oil to the dies, and means for locking said shifting means against displacement.

In testimony whereof I affix my signature hereto.

CHARLES F. SCHMELZ.
